SCAFFOLD HOIST HOLDING MEANS

Hobart S. Geer, Jackson Heights, N. Y., assignor
to The Patent Scaffolding Co., Inc., Long
Island City, N. Y., a corporation of New York

Application December 13, 1947, Serial No. 791,590

2 Claims. (Cl. 74—528)

1

This invention relates to scaffold hoists and more particularly to clutches for the same.

Heretofore, scaffold hoists have used worm and worm gear connections for controlling the action of the winding drum. The means for operating the worm have not been too safe, and it is one of the objects of this invention to improve such operating means so as to increase the safety of the same.

The invention consists of an improved clutch on the worm shaft, consisting of two parts each having teeth which engage each other, one of said parts being formed into a sleeve having a bracket with a pin passing through a slot of the handle, the handle being pivoted to the shaft, on which a helical spring is disposed, the spring tending to cause the teeth of the sleeve to mesh with the teeth of the worm sleeve, and the handle being operated against the action of the spring, the handle when in one position being prevented from rotating by the frame of the hoist, and when in the other, being free to rotate without obstruction by the hoist frame.

The invention will be further described, embodiments of the same will be shown in the drawings, and the invention will be finally pointed out in the claims.

In the accompanying drawings,

Fig. 1 is a side view of a scaffold hoist frame with the improvement embodied therein;

Fig. 2 is a partial front view of a frame, with the improvement embodied therein;

Fig. 3 is an enlarged section of the improvement, taken on line 3—3 of Fig. 1;

Fig. 4 is a fragmentary view showing the intermeshing teeth, and handle operated sleeve;

Fig. 5 is a side view of another embodiment of my improvement; and

Fig. 6 is a section taken on line 6—6 of Fig. 5.

Similar characters of reference indicate corresponding parts throughout the various views.

Referring to the drawings, (Fig. 1), the worm shaft 10, has a worm 11, meshing with a worm gear 12, as known.

The improvement consists in securing to the worm shaft 10 adjacent to the worm 11, a clutch member 13 consisting of a sleeve 14 having one end 15 in a plane perpendicular to the shaft 10, and the other end 16 provided with teeth 17, each having an inclined part 18, and a shoulder part 19.

A sleeve 20 has at one end 21, teeth 22 to register with the teeth 17, each tooth having an inclined part 21 and a shoulder part 19a. The sleeve 20 has its bore 23 concentric with the shaft 10. The sleeve 20 has a depending plate 28 from both

sides of which, a pin 29 extends. The sleeve 20 also has a slot 35 at each side thereof. A forked handle 30 with forks 32 has a slot 31 for freedom of movement in respect to the pins 29 on the plate 28. The handle 30 is secured to a pin 34 passing through the slots 35 of the sleeve 20, which pin 34 passes through a circular slot or hole 10a in the shaft 10. The free end 36 of the handle 30 has a hand portion 37 at right angles thereto.

A helical spring 38 has one end pressing against the end 39 of the sleeve 20, and its other end 40 pressing against a washer 41 on the shaft 10, which washer 41 abuts against a pin 42 secured to the end of the shaft. The spring 38 tends to push the sleeve 20 in a direction to keep the teeth of the sleeves intermeshing. When so intermeshing, the handle 30 is in inward or inclined position as shown in full lines in Fig. 1. When the handle 30 is so inclined it would, if rotated, by the reason of the worm connection, abut against some part of the frame of the hoist, and thus prevent further rotation.

If it is desired to cause the hoist to descend in the manner well known, the handle 30 is moved from its oblique position to a position perpendicular to the shaft 10, as shown in dotted lines in Fig. 1, whereby the sleeve 20 is drawn away so as to free the teeth from each other, and the spring 38 is compressed. Then the worm 11 can be operated by the rotation of the handle 30, by the rotation of the shaft 10.

On release of the handle, the spring 38 forces the sleeve 22 back to its intermeshing position, and the handle back to its oblique position.

The improvement described is applied to the known scaffolding hoist. This consists of a frame 50, only one side wall of which is shown in Fig. 2. The lower part of the frame 50 is secured to its companion member (not shown) by tie bars 51, and the upper parts are secured together by a tie bar 52. A shaft 53 having its ends rotatable in the frame 50, has a pinion 54, which meshes with the gear 55 of a disc 56 forming part of a drum 57 upon which a cable is wound (Fig. 2). Upon the outside of the disc 56, pawls 58 are secured which are pressed by springs 59 against a ratchet 60 loosely mounted on the shaft 61 of the drum 57, the shaft 61 being supported by the frame 50. In the embodiment, the ratchet 60 is made a part of a member 62 having the worm gear 12, which meshes with the worm 11. The disc 56 is integral with the drum 57.

When it is desired to raise the hoist, the shaft 61 is rotated by the pinion 54 anticlockwise, as shown by the arrow 60a (Fig. 1), which permits

the pawls 58 to ride on the ratchet teeth 60, and causes the worm gear to rotate the worm 11, the teeth 17 simply riding on the teeth 22 of the clutch. When it is desired to lower the hoist, the shaft 10 is rotated by the handle 30, which is held in the dotted line position shown in Fig. 1, whereby the teeth 17 and 22 are out of engagement.

The improvement consists in the provision of the toothed sleeve 20 slidable on the shaft 10 having a supporting bracket 28 to which the handle 30 is pivoted, which handle 30 is pivoted to the shaft 10 by the pin 34. By the movement of the handle 30 to vertical position from its inclined position as shown in full lines, the bracket 28 is moved, outwardly, to a distance against the action of the spring 38, sufficient to disengage the teeth 22 from the teeth 17, which enables the worm 11 to be rotated by the shaft 10, when lowering the frame 50.

In Figs. 5 and 6 is shown an alternate form, wherein the spring is placed in another position, the parts otherwise operating as described.

In the embodiment shown in Figs. 5 and 6, the sleeve 20 to the rear of the shaft 10 has two lateral rearwardly extending members 22a, each having a slot 35. Within these members 22a, a helical spring 38a surrounds the shaft 10 and has one end seated against the inner part of the sleeve. A disc 41 surrounds the shaft 10, and abuts against the other end of the spring 38a. A pin 42 passes through the shaft 10, and the disc 41 abuts against it. The members 42a extend downwardly to form a bracket 22a each having a slot 31a, for the movement of the pin 29a therein, which pin is secured to the handle yolks 32. These yolks are pivoted to the pin 34 passing through the shaft 10, the slots 35 permitting movement of the sleeve 22 with its members 22a in respect to the pin 34.

The mode of operation of the modified embodiments is the same as the embodiment of Figures 1 to 4. When the handle 30 is in the full line position of Fig. 5, the teeth engage each other. When the handle 30 is moved from the full line to the dotted line position, then the sleeve 22 with its members 22a has been moved so as to disengage the teeth, and the spring 38a has been compressed thereby tending to again intermesh the teeth.

I have described several forms of my invention, but obviously various changes may be made in the details disclosed without departing from the spirit of the invention as set out in the following claims.

I claim:

1. In a scaffold hoist brake having a worm shaft and a non-rotatable housing for the worm shaft, the combination of teeth on said housing, a sleeve mounted slidably on said shaft, teeth on said sleeve for meshing with the teeth of the housing, a bracket on said sleeve, a handle pivoted to the worm shaft and pivotally connected with the bracket, and a helical spring surrounding the shaft and pressing the sleeve teeth towards the teeth of the housing, the outward movement of the handle compressing the spring and moving the sleeve to disengage the teeth of the sleeve from the teeth of the housing and permit rotation of the worm, the release of the handle and its inward movement by the pressure of the spring moving the sleeve, and engaging said teeth and automatically locking the worm, against rotation.
2. In a scaffold hoist brake having a rotatable worm shaft, and a non-rotatable housing for the worm shaft, the combination of teeth on said housing, a sleeve mounted slidably on said shaft, teeth on said sleeve engageable with the teeth of the housing, a bracket on said sleeve, a handle pivoted to the worm shaft and having a slot pivotally connected with the bracket, a cross pin on the worm shaft to which said handle is pivoted, a helical spring surrounding the shaft and pressing the sleeve towards the teeth of the housing, and compressed by the outward movement of the handle, and a cross pin on the worm shaft to hold one end of the spring from moving, the outward movement of the handle moving the sleeve outward to disengage the teeth, and permit rotation of the worm shaft during the lowering of the hoist, the release of the handle permitting the spring to move the sleeve and engage the teeth and lock the shaft to the housing, to automatically brake the downward movement of the hoist, in the event of loss of control by the operator.

HOBART S. GEER.
